(57) **CLAIM**

I claim the ornamental design for a switch, as shown and described.

DESCRIPTION

FIG. 1 is an isometric view of a switch showing my new design.

FIG. 2 is a front elevational view of FIG. 1.

FIG. 3 is a left side elevational view of FIG. 1.

FIG. 4 is a right side elevational view of FIG. 1.

FIG. 5 is a bottom plan view of FIG. 1.

FIG. 6 is a top plan view of FIG. 1.

FIG. 7 is an isometric view of a second embodiment of the design of FIG. 1.

FIG. 8 is a front elevational view of FIG. 7.

FIG. 9 is a left side elevational view of FIG. 7.

FIG. 10 is a right side elevational view of FIG. 7.

FIG. 11 is a bottom plan view of 7; and,

FIG. 12 is a top plan view of FIG. 7.

The rear of all six embodiments forms no part of the claimed design.

The broken line showing of environmental structure in all views of the drawings is for illustrative purposes only and forms no part of the claimed design.
